UNITED STATES PATENT OFFICE.

EUGENE JACQUEMIN, OF KENT, WASHINGTON.

CORK-EXTRACTOR.

1,094,997.

Specification of Letters Patent. Patented Apr. 28, 1914.

Application filed August 5, 1913. Serial No. 783,109.

To all whom it may concern:

Be it known that I, EUGENE JACQUEMIN, a citizen of the United States, residing at Kent, in the county of King and State of Washington, have invented new and useful Improvements in Cork-Extractors, of which the following is a specification.

The invention relates to cork extractors, and more particularly to the class of combined cork extractors and metal cap removers.

The primary object of the invention is the provision of a device of this character wherein a cork when inserted in a bottle neck can be readily and easily removed without requiring excessive exertion on the part of the user, nor mutilating the cork when drawn from the bottle neck.

Another object of the invention is the provision of a device of this character wherein the handle portion is of novel form so as to be capable of use for removing metal caps from bottle necks.

A further object of the invention is the provision of a device of this character wherein a cork can be extracted from the neck of a bottle on the turning action of the device, thereby obviating the necessity of pulling the cork from the bottle neck as is usual.

A still further object of the invention is the provision of a device of this character which is simple in construction, thoroughly reliable and efficient in its purpose, and inexpensive in manufacture.

With these and other objects in view, the invention consists in the construction, combination and arrangement of parts as will be hereinafter fully described, illustrated in the accompanying drawing, and pointed out in the claims hereunto appended.

In the drawing: Figure 1 is a perspective view of a device constructed in accordance with the invention. Fig. 2 is a fragmentary vertical sectional view through a bottle showing the device applied for removing the cork from the bottle neck. Fig. 3 is a fragmentary perspective view of a bottle with a metal cap showing the device applied for removing said cap. Fig. 4 is a side elevation of the device.

Similar reference characters indicate corresponding parts throughout the several views in the drawing.

Referring to the drawing by numerals, the device comprises a pair of spaced legs 5 and 6, the latter being of greater length than the leg 5, and both of which have flattened portions 7. The inner ends of the legs are joined to a twisted portion 10 which connects a looped handle 11 therewith, the same being formed with bights 12 providing jaws arranged in juxtaposition with respect to each other and projected into the looped handle 11 as shown. The legs 5 and 6 are curved outwardly as at 8 and 9 respectively, beyond opposite sides of the plane of the looped handle, so that they will serve to lift a cork when the legs are inserted between the bottle neck and the said cork and the extractor is twisted for the loosening of the cork in the bottle neck. This looped handle 11 is adapted to be engaged with a metal cap 13 so that a stretch thereof will overlie the latter while the jaws 12 will engage the edge of the said cap 13 as is illustrated in Fig. 3 of the drawing so that on pulling upwardly on the legs 5 and 6 the cap will be removed from the bottle neck.

When the device is used as a cork extractor the legs 5 and 6 are inserted between a cork 14 and the neck 15 of the bottle, the leg 6 being longer than the leg 5 permits the initial insertion of the said leg 6 between the cork and the bottle neck, and after these legs have been inserted the proper distance within the bottle neck the looped handle is grasped and turned, thereby loosening and removing the cork from the bottle neck.

From the foregoing it is thought that the construction and manner of operation of the device will be clearly understood, and therefore a more extended explanation has been omitted.

What is claimed is:—

1. A cork extractor comprising a pair of spaced resilient legs and a handle, both of said legs being outwardly curved in reverse directions to each other at opposite sides of the plane of the handle, one of said legs being of greater length than the other.
2. A cork extractor comprising a pair of

spaced resilient legs and a handle, both of said legs being outwardly curved in reverse directions to each other at opposite sides of the plane of the handle, one of said legs being of greater length than the other, said legs being flattened for a portion of their lengths.

In testimony whereof I affix my signature in presence of two witnesses.

EUGENE JACQUEMIN.
